FRONT-BAND CONSTRUCTION FOR FIREARMS

Ralph E. Clarkson, Hamden, Conn., assignor to
 Western Cartridge Company, New Haven,
 Conn., a corporation of Delaware

Application December 9, 1941, Serial No. 422,217

1 Claim. (Cl. 42—75)

The present invention relates to improvements in firearms and relates more particularly to improvements in the construction of the front-bands of firearms which serve to couple the stock to a barrel.

The present invention is primarily designed for use with self-loading repeating firearms of the military type, though not so limited, since such firearms are especially subjected to very rapid fire which causes excessive heating of the barrel.

It may here be noted that one of the deleterious effects of a very hot barrel is that of charring the stock of the firearm if the stock or its equivalent is closely fitted to the barrel in accordance with standard practice. Prior efforts to provide adequate clearance between a stock and its complementary barrel, in order to minimize or avoid charring, have been open to various serious objections, among which may be mentioned undue looseness of the parts and binding and deflecting action upon the barrel.

One of the objects of the present invention is to provide a superior front-band construction for firearms which will reliably and securely unite a stock to a barrel.

Another object of the present invention is to provide a superior front-band construction for firearms by means of which a stock may be effectively held in spaced relationship with respect to a barrel, to minimize damage to such a stock as a result of excessive heating incident to the rapid and continued discharge of the firearm of which the said barrel and the said stock form a part.

A further object of the present invention is to provide a superior front-band construction which will effectively hold a stock or its equivalent in spaced relationship with respect to a barrel and which will, at the same time, avoid the distortion of the said barrel as an incident to the coupling of the stock thereto.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken view in side elevation of the forward portion of a military firearm having a front-band construction embodying the present invention;

Fig. 2 is a side view thereof in vertical central-longitudinal section;

Fig. 3 is a transverse sectional view taken on the line 3—3 of Fig. 1;

Fig. 4 is a similar view taken on the line 4—4 of Fig. 1;

Fig. 5 is a view of the front-band detached and viewing the same from the rear;

Fig. 6 is a view of the front-band detached viewing the same from the front thereof;

Fig. 7 is a sectional view taken on the line 7—7 of Fig. 5; and

Fig. 8 is a perspective view of the locating-band member, detached.

In the particular front-band and associated structure herein chosen for purposes of illustrating the present invention, a front-band 10 is employed which is of generally tubular form and which fits over a firearm-barrel 11 adjacent the muzzle-end thereof and receives a portion of a stock 12 and barrel-cover or hand-guard 13. The front-band itself is preferably formed of high-grade forged steel, as is also the barrel 11, while the stock 12 and barrel-cover 13 are preferably formed of wood or other suitable heat-insulating material.

The front-band 10 comprises in the structure shown a tubular body-member 14 and a ring-like locating-band 15 which latter is sized to snugly fit over the adjacent portion of the barrel 11 and having its under portion extending beneath the said barrel to provide what may be termed, for convenience of description, an upwardly-facing stop-abutment 16 for purposes as will hereinafter appear.

The body-member 14 of the front-band unit 10 is formed with a transverse notch 17 of a depth extending substantially to the axial center of the barrel 11 and resulting in the formation at the upper portion of the front end of the said body-member of a front strap-portion 18 extending around substantially the upper half of the barrel 11. The notch 17 just referred to also results in the formation at the rear upper portion of the body-member 14 of a rear strap-portion 19 also extending around substantially all of the upper half of the barrel 11. Throughout the major portion of its width, the rear strap-portion 19 of the body-member 14 conforms to the contour of the upper portion of the barrel 11 and is radially spaced therefrom, but at its rear end the said rear strap-portion 19 is enlarged to form a substantially-semicircular retaining-lip 20 within which fits a substantially-semicircular tenon 21 formed at the forward end of the barrel-cover 13. The rear edge of the retaining-lip 20 just referred to

is normally seated against a forwardly-facing shoulder 22 formed on the barrel-cover 13 at the rear of the tenon 21 thereof.

The forward portion of the stock 12 is reduced in size to provide a forwardly-projecting tenon 23 extending through the lower portion of the body-member 14 and beyond the front end thereof. At the rear of its said tenon 23, the stock 12 is formed with a forwardly-facing shoulder 24 normally aligned with the shoulder 22 of the barrel-cover 13 and seated against the rear edge of the said body-member 14, as will be apparent by reference to Figs. 1 and 2 in particular.

The stock 12 is formed in its upper face with a longitudinally-extending groove 25 of substantially-semicircular form in cross section and having a transverse shape and dimension sufficient to amply clear the under portion of the barrel 11, to provide a longitudinal ventilation-passage preferably opening through the extreme forward end of the said stock. The said stock 12 is preferably so dimensioned that its upper edges on each of the respective opposite sides of the barrel 11 are located about midway of the vertical thickness of the said barrel. Similarly, the barrel-cover 13 is formed in its under face with a longitudinal groove 27 of substantially-semicircular form in cross section and having a transverse dimension sufficient to provide a longitudinal ventilation-passage around the upper portion of the barrel 11.

As will be seen by reference to Figs. 3 and 4 in particular, the respective lower edges of the barrel-cover 13 normally rest upon the respective upper edges of the stock 12 on each of the respective opposite sides of the barrel 11.

The front strap-portion 18 of the body-member 14 is of substantially-semicircular form in cross section and is proportioned to snugly receive in its interior substantially the entire upper half of the locating-ring 15 before referred to. In the instance shown, the locating-ring 15 is rigidly attached to the body-member 14 by means of two (more or less) rivets 29-29 extending respectively in diverging directions through the upper portion of the locating-ring 15 and through the adjacent portions of the front strap-portion 18 of the said body-member 10. Preferably the locating-ring 15 is formed in its periphery with an annular groove 30 in the upper portion of which may be positioned a length of copper wire or its equivalent. After the locating-ring 15 has been secured to the body-member 14 by the rivets 29-29 or other suitable means, the entire structure may be heated in a non-oxidizing atmosphere to melt such copper or other soldering or brazing material as may be located in the upper portion of the groove 30, with the effect of melting such copper and causing the same to spread by capillary action between the inner face of the front strap-portion 18 and the juxtaposed portion of the locating-ring 15. Upon being permitted to cool, the copper or its equivalent will solidify and will serve to rigidly unite the locating-ring 15 with the body-member 14, in a manner capable of withstanding the severest shocks without rupture.

The forward portion of the body-member 14 on its underside may be provided, as shown, with a bayonet-lug 31 adapted to be engaged by and to support the handle end of a bayonet (not shown) in a manner well known in the art of military firearms.

Adjacent its rear edge, the body-member 14 is formed on its underside with two laterally-spaced-apart and depending-ears 32-32 receiv-

ing between them the upwardly-projecting tang 33 of a strap-swivel 34. The said strap-swivel 34 is secured to the body-member 14 with capacity for pivotal movement in a direction longitudinally of the firearm, by a screw or stud 35 extending through the ears 32-32 and through the tang 33, referred to.

Adjacent its rear edge, the body-member 14 of the front band-unit 10 is formed in its opposite sides respectively with coaxial passages 36 and 37 located in a horizontal plane slightly beneath the under face of the barrel 11.

Extending transversely through the tenon 23

of the stock 12 and seated at its respective opposite ends in the passages 36 and 37 of the body-member 14, is a retaining-pin 38 which serves to couple the entire front-band unit 10 to the stock 12 against forward displacement with respect thereto. As is shown particularly well in Fig. 3, the body-member 14 is formed in its left side wall with a vertical pocket 39 having its lower end intersecting the top of the passage 36 and accommodating a helical compression-spring 40 and a locking-plunger 41. The spring 40 just referred to serves to normally hold the lower end of the locking-plunger 41 seated in the adjacent one of two locking-recesses 42-42, one of which is formed adjacent each of the respective opposite ends of the retaining-pin 38 before referred to.

Preferably and as shown, the locating-ring 15 is formed separately and then rigidly united with the body-member 14 for purposes of economy of manufacture. Preferably also, the said locating-ring completely encircles the adjacent portion of the barrel 11 though this is not essential so long as a stop-abutment such as 16 is provided which will prevent the front-band unit from moving upwardly with reference to the barrel 11.

By reference to Figs. 1 to 4 inclusive, it will be apparent that the forward portion of the stock 12 is prevented from moving upwardly toward the barrel 11 by the retaining-pin 38 and by the engagement of the respective upper side edges of the said stock with the complementary under edges of the barrel-cover 13. Even in the absence of the retaining-pin 38 or its equivalent, the stock 12 would be prevented from moving upwardly by the barrel-cover 13, since the said barrel-cover, in turn, is prevented from being displaced upwardly by the retaining-lip 20 and the tenon 21.

Since the stock 12 is stabilized against upward displacement with respect to the front-band unit 10, and since the said front-band unit is prevented from upward displacement with respect to the barrel 11 by the stop-abutment 16 or its equivalent formed by the under portion of the locating-ring 15, the said stock 12 may be held in spaced relationship with respect to the underside of the barrel 11 in such manner as to provide adequate ventilation and a heat-insulating space. In this manner, the stock 12, as well as the barrel-cover 13, is prevented from being materially damaged by heat emanating from the barrel 11 despite the fact that the said barrel, on occasion, will approach almost a red heat when the firearm is rapidly discharged over considerable periods of time.

The invention may be carried out in other specific ways than those herein set forth without departing from the spirit and essential characteristics of the invention, and the present embodiments are, therefore, to be considered in all respects as illustrative and not restrictive, and all changes coming within the meaning and

75

2,371,282

3

equivalency range of the appended claims are intended to be embraced therein.

I claim:

A firearm-structure including in combination: a barrel; a stock located adjacent the underside of the said barrel and covering substantially the under half of the said barrel but in spaced relationship thereto; a barrel-cover located adjacent the upper side of the said barrel and covering substantially the upper half of the said barrel but in spaced relationship thereto, the said barrel-cover having the under faces of its respective opposite sides engaged with the upper faces of the respective opposite sides of the said stock;

5 a tubular front-band unit fitting over the said barrel and also over portions of the said stock and the said barrel-cover; and a locating-ring encircling the said barrel and rigidly attached to the said front-band unit within the upper portion thereof and extending into engagement with the under portion of the said barrel at a point between the latter and the said stock, the said locating-ring being out of contact with the said 10 stock and holding the said front-band unit and hence the said stock against displacement transversely relative to the said barrel.

RALPH E. CLARKSON.
